I. JENNINGS.
SPIRIT LAMP.

Patented Aug. 1, 1831.

NO PRINTED COPY OF SPECIFICATION IN OFFICE.

Osacah Movings X 1080

The substance referred to in the Buller Patent and
making part of the claim containing a description
in the name of the said Osacah Movings himself
of his improvement in lamps for burning combustible
ingredients.

No all of whom it may concern. be it known that
J. Osacah Movings of the City of New York have
invented an improvement in the common lamp which
adopts it especially to the combustion of combustible
of alcohol and of spirits of turpentine, and of other essen-
tial oils and ingredients, for the use of which signs
prior-patents of the United States have been
already issued to me and which improvement in the
lamp is also applicable to the combustion of other combustible
ingredients not specified in the Buller Patent
above alluded to. and I do hereby declare that
the following is a full and exact description of my
said improvement in the lamp.

Instead of the tube constructed in the ordinary man-
ner, for containing the cotton or other wick which is
in them allowed to project through the tube or
barrel, and lighted at the top thereof. I make a tube
or other tube which causes to rise to a much greater
height above the reservoir, or body of the lamp than
is usually done, say for example to the height of two
inches. the upper end of this tube I close entirely or com-
pletely with a small hole therein of such size as may suit
the ingredients to be burned; but not greater than ex-
ceeding one thirtieth of an inch in diameter. Through
the body of the said tube and at about half an inch
from the lower end, there is joined the
body.

body of the lamp. I will give on my other number of this
the holes. The tube thus constructed forms the main
feature of my improvement, and in order to use this
lamp, I insert a wick of cotton, a bundle of fine
silk, or any other fibrous material, which will raise
the fluid from the lamp by capillary attraction;
allowing the wick to rise to the upper end of the tube, and
and to descend into the fluid the vapour of which is to
be burnt. When this lamp is to be lighted all that
is necessary is to apply flame to the small opening above
described. When the vapour which escape therefrom will
be inflamed, and the heat generated by this inflam-
mation operating upon the tube will incinerate the vapour
so as to produce a brilliant light without the
destruction of the wick or other fibrous substance.

What I claim as new and as my improvement in
the lamp and which is applicable to such lamps as
are now in use is the tube or bundle for containing the
wick or other fibrous substance, constructed in the man-
ner or upon the principle herein before explained.

Witness

Thos J. Jones
